UNITED STATES PATENT OFFICE.

AUGUSTUS STEVENSON, OF KITTERY, MAINE.

IMPROVEMENT IN MACHINES FOR BENDING TIMBER.

Specification forming part of Letters Patent No. **154,099**, dated August 11, 1874; application filed June 27, 1874.

To all whom it may concern:

Be it known that I, AUGUSTUS STEVENSON, of Kittery, York county, in the State of Maine, have invented certain new and useful Improvements in Machines for Bending Timber for boats and other larger vessels; and I hereby declare the following to be a full and exact description thereof, reference being had to the accompanying drawings forming part of this specification.

The nature or essence of my invention consists in the particular construction, combination, and arrangement of devices forming the improvements described in the following specification and represented in the drawings, in which drawings—

Figure 1 is a plan of a machine for bending wood with my improvements. Fig. 2 is an elevation of one side of the same. Fig. 3 shows a piece of wood in a protecting-strap, arranged for bending in one direction only.

In the above-mentioned drawings, A is the platform or table upon which the other parts are applied or fastened. To the table A I fasten the forms or molds B B, for bending wood in one direction only, and the mold C to bend it in the opposite direction. These molds are made to give the desired form to the wood bent on them, and are provided with flanges D D, Fig. 2, to prevent the wood from spreading widthwise when it is being bent. These molds are fastened to the table A by bolts or screws E E, which pass through them and through the blocks F F, which support the molds a proper distance from the table, to allow the ropes or chains with which the machine is worked to pass freely under the molds; and also to allow screw-clamps to be applied under the molds to clamp the wood fast to them as it is bent. In the outer ends of the molds B I put pulleys G G, for the ropes or chains to run over. The pulleys G are made narrower than the grooves in the molds, and put so far in from the ends that the metal protecting-strap when applied to that end of the mold, will not bind the pulley. To bend the ends of the piece of timber H in opposite directions, for the after-cants or timbers of a boat or vessel, I take a thin bar of metal, I, narrow enough to work freely in the grooves in the molds, and fasten one end to

the mold B with a screw and arm, the opposite end with a strong jaw, K, provided with a traversing - plate, K', and an adjusting-screw, L, to press the plate K' against the end of the timber H. To the jaw K I apply a becket or ring, M, and rope N, and lead it through the ring N¹ to the windlass P, which is mounted on the platform in proper journal-boxes, as shown in the drawing. This windlass P is provided with a gear, P¹, which projects down through the table A and is turned by the endless screw P² on the shaft Q, which is mounted in proper journal - boxes Q' Q' on the under side of the table A, and provided with crank Q² to turn the screw P², and operate the windlass and wind up the rope to draw the timber H around the mold C, and bend it in the form desired. A thin bar of metal, I', is fastened to the mold C at C², and is provided with a jaw - plate and screw, the same as the strap I, heretofore described, and a rope, N², from the ring M¹, is led through the ring M², and by the pulleys G and G' to the windlass R, so that one end of H may be bent in one direction while the other end is bent in the opposite direction. The timber H is properly steamed, in a manner well known to workers in wood, and put into the machine and bent while it is wet and hot, and may be held to the molds, until it is cooled and dried, by the ropes which bend it; or screw-clamps, W, Fig. 1, may be applied to hold it to the molds and the ropes released.

The power of this machine may be increased by using tackle - blocks with two or more sheaves wherever great power is required.

The journal-boxes at the crank-ends of the shafts Q are supported by the screw - bolts S S, and the nuts of these bolts may be turned to drop the endless screws P² out of the gear P¹, and allow the windlass to be turned back to unwind the rope N. It is found to be a great advantage to have flanges on the molds to prevent the wood bent from spreading widthwise on the mold. To bend a piece of wood in one direction only on the molds B B, I use a protecting-strap, such as is shown in Fig. 3, and reeve a rope from each end, like N². The holes T T in the table are for the purpose of adjusting the molds, so as to bend the wood more or less, as desired.

What I claim as my invention and improvements in the above-described wood-bending machine is—

1. The combination of the endless screws P^2 , gear P^1 , windlass P , ropes or chains N N^2 , pulleys G G' , protecting-straps I I' , molds B , B , and C , all constructed as and for the purpose described.

2. In a wood-bending machine, in combination with the gears, the boxes of the endless screws, made movable to release the endless screw from the gear, as described.

AUGUSTUS STEVENSON.
